UNITED STATES PATENT OFFICE.

JOHN WILLIS WEAVER, OF RALEIGH, NORTH CAROLINA.

GAME APPARATUS.

Application filed March 5, 1925. Serial No. 13,259.

To all whom it may concern:

Be it known that I, JOHN W. WEAVER, a citizen of the United States, and resident of Raleigh, in the county of Wake and State of North Carolina, have invented certain new and useful Improvements in Game Apparatus, of which the following is a specification.

My invention relates to a game apparatus, more particularly to apparatus for use in playing a game which involves the elements and principles of the game of baseball, and it consists in the combinations, constructions and arrangements herein described and claimed.

An object of the invention is the provision of a game apparatus of the character described which will afford facilities for the playing of a game which is in the similitude of the usual hand played game of baseball and which will involve elements, conditions and circumstances closely approximating like elements, conditions and circumstances of the actual game of baseball so that the result of the game will be determined both by chance and the differential of skill between the opposing players of the game.

Another object of the invention is the provision of a game apparatus of the character described having playing units and equipment functioning during the playing of the game to bring about conditions, situations and results practically identical with the conditions, situations and results of the actual game of baseball.

A further object of the invention is the provision in an apparatus of the character described of a novel pitching mechanism which is operable according to the skill of the manipulator thereof to determine the course that the ensuing play shall take and therefore to determine to a large extent the final outcome of the game.

A still further object of the invention is the provision in a game apparatus of the character described of a novel arrangement of stop elements and actuating mechanism which will function to permit or prevent movement of a base running element according to whether or not a base runner would be permitted to advance or prevented from advancing in like circumstances in the actual game of baseball.

Other objects and advantages of the invention will be apparent from the following

description, considered in conjunction with the accompanying drawing, in which—

Figure 1 is a perspective view of the improved game apparatus with the cover of the case omitted.

Figure 2 is a plan view of the apparatus with the field surface structure omitted,

Figure 3 is a central vertical section through the complete apparatus with the cover of the case in place, the view being taken substantially along the line 3—3 of Fig. 2.

Figure 4 is a fragmentary perspective view showing the vertically movable second base and third base stop of the apparatus together with the independent release mechanism for the third base stop,

Figure 5 is a fragmentary perspective view, showing a corner portion of the game apparatus, including the back stop, the batting mechanism and parts associated therewith and showing also the central or main motion transmitting member of the actuating mechanism for the several base stops,

Figure 6 is a perspective view of the pitching mechanism and its support,

Figure 7 is an end view of the structure exhibited in Figure 6,

Figure 8 is a perspective view showing the base stops together with the main or central actuating member of the mechanism for operating the stops, the connections between the central actuating member and the respective base stops and the connections between a plurality of operating members and the central actuating member,

Figure 9 is a perspective view showing the base stops and the operating mechanism therefor exclusive of the central actuating member and its connections, and

Figure 10 is a perspective view showing the first base stop, the outfield operable operating mechanism for the first base stop and the outfield operable mechanism for actuating the second base stop.

The improved game apparatus is housed in a case which preferably is rectangular in cross sectional contour. The case is best seen in Figures 1 to 3 and may comprise a flat bottom 1, vertical marginal walls 2 upstanding from the bottom, and a removable cover 3 which can be secured in place on the vertical walls of the case in any suitable known manner, as by means of the catches or clips indicated at 4 in Figure 1. 5 may be secured on one vertical wall of the case and the case may be provided with handles also, as indicated at 6, so that the case and the apparatus therewithin can be readily moved on a supporting surface when the case is closed and has been uptilted from its normal position to rest upon the casters 5.

10 The playing field or game board is supported in the case, as by being secured to fixed supporting members such as indicated at 7 and 8 respectively in Figure 3, so that sufficient space will be provided between the game board and the bottom of the case for the reception of operating mechanism to be 15 presently described and at the same time portions of the vertical wall of the case will extend above the level of the highest portion of the game board and will serve as "fences" for the playing field.

20 The game board is formed to provide an infield, indicated at 9 in Figure 1, and an outfield which is separated from the infield by a runway in the form of a groove or channel 10 in the surface of the game board.

25 The infield is of the usual "diamond" shape. The portion of the game board at the head of the infield constitutes a "batter's box" as indicated at 11. A backstop 12 is upstanding at the rearward end of the "batter's box" 30 and the latter is flanked by a pair of upstanding guard members 13. These side guard members 13 are secured to the backstop 12 at opposite ends of the latter and may extend rearwardly of the back stop as 35 shown in Figure 1 for connection with the vertical walls 2 of the case of the apparatus, whereby a space may be defined in the case between the backstop 12, the rearward extensions 13^a of the side guards 13 and the inner walls of said corner portions of the case. Certain operating mechanism of the 40 apparatus which will be hereinafter described is disposed in the space within the case back of the backstop 12 and between the rearward extensions 13^a of the side guards 13.

45 The runway 10 terminates at one end at the right hand side of the right hand guard member 13, considering the game board as being viewed from the batter's box, looking in the direction of the middle portion of the outfield. The corner portions of the runway constitute "bases" and beginning at the right hand end of the runway, the runway is 50 formed at suitable places along its length to provide a first base 14, a second base 15 and a third base 16. The runway slopes gradually and regularly from its right hand end throughout its length and is merged at its 55 other end into a groove 17 which extends in the surface of the game board at the left hand side of the batter's box 11. The groove 17 slopes rearwardly from its junction with the left hand end of the runway 10 and may be termed the "home base,"

60 A channel 18 is formed in the game board to extend directly across the infield from the right hand portion of the batter's box 11 to the right hand end of the second base portion 15 of the runway 10. The channel 18 70 slopes gradually and regularly from the level of the batter's box 11 at one end of the channel 18 to the level of the second base portion 15 of the runway 10 at the other end of the channel 18. The game board 75 also is formed to provide a channel 19 which extends from the left hand portion of the batter's box across the infield nearly to the left hand end of the second base portion 15 and then is merged into a return channel 20 80 which is merged at its rearward end into the home base groove 17 at the juncture of the latter with the left hand end of the runway 10. The bottom wall of the channel 19 is level at its rearward end with the batter's 85 base 11 and then slopes regularly and gradually toward its juncture with the forward end of the channel 20. The latter slopes from its juncture with the channel 19 toward its juncture with the home base 17. 90

95 A channel 21 is provided in the game board to extend obliquely across the outer field from the first base portion 14 of the runway 10 to the right hand corner of the case. The game board also is formed with a channel 22 which extends obliquely across the outer field from the second base portion 15 of the runway to the vertical walls of the case at the middle corner of the outer field. A channel 23 extends in the surface of the 100 game board from the third base portion 16 to the vertical walls of the case at the left hand corner of the outer field. These channels 21, 22 and 23 slope regularly and gradually from their outer ends to their junctures with the indicated portions of the runway 10. A vertically edgewise division plate or fin 24 extends directly across the outer field from a point on the runway 10 midway between the first base 14 and the 105 second base 15 to the adjacent vertical wall of the case. A similar division plate or fin 25 extends directly across the outer field from a point on the runway 10 midway between the second base and the third base 110 to the adjacent vertical wall of the case. 115

120 The portion of the outer field that extends between the division fin 24 and the groove 21 is indicated at 26 and constitutes the right field fair territory but will be referred to hereinafter simply as "right field". The portion of the outer field which extends between the channel 21 and the guard member 13 at the right hand side of the batter's box constitutes right hand foul territory and is indicated at 27. The right field 26 slopes throughout its area toward both the channel 21 and the adjacent portions of the runway 10. The "foul" territory 27 slopes from its junction with the adjacent vertical wall of 125 130

the case toward the channel 21 and adjacent portion of the runway 10.

The portion of the outerfield that extends between the division fins 24 and 25 constitutes the "center" field. The center field comprises a right hand section that is located between the channel 22 and the division plate 24 and a left hand section which is located between the division plate 25 and the channel 22. The right hand section of the center field comprises an outer portion 28 that slopes from the division plate 24 toward the outer end portion of the channel 22, an intermediate portion 29 that slopes 15 from the division plate 24 toward the channel 22 and is divided from the outer portion 28 for part of the distance from the division plate 24 to the channel 22 by a rib or crest 30, and an inner portion 31 which is divided 20 from the intermediate portion 29 for part of the distance from the division plate 24 to the channel 22 by a rib or crest 32. The inner portion 31 of the right hand section of the center field slopes throughout its area 25 toward the adjacent portion of the runway 10 and may slope adjacent to the channel 22 toward that channel. The left hand section of the center field comprises an outer portion 33 which slopes from the division plate 25 toward the extreme outer end portion of the channel 22 and is provided with a channel 34 which extends alongside the adjacent vertical wall of the case or in other words 30 at the extreme outer edge of the portion 33 from the division plate 25 to the central corner of the center field, at which point it is merged into the outer end of the channel 22. The center field also includes an inner portion 35 which is divided from the outer portion 33 by a ridge 36 which extends from the division plate 25 part of the distance to the channel 22. The portion 35 of the left hand section of the center field slopes throughout its area both toward the channel 22 and toward the adjacent portion 35 of the runway 10. The portion of the outer field that extends between the division plate 25 and the channel 23 constitutes the left field fair territory of the game board and will be hereinafter referred to simply as the "left field". The left field includes an outer portion 37 which slopes from the division plate 25 outwardly toward a channel 38 which extends alongside of the adjacent vertical wall of the case from the division plate 25 to the outer end of the channel 23. The left field also includes an intermediate portion 39 which slopes toward the meeting end portions of the channels 38 and 23 and is divided from the outer portion 37 by a ridge 40 and from an inner portion 41 of the left field by a ridge 42. The inner portion 41 of the left field slopes throughout its area toward the adjacent portion of the runway 10 and the portion thereof adjacent

to the channel 23 also slopes toward that channel.

The portion of the outer field which extends between the channel 23, left hand end portion of the runway 10, home base 17 and the adjacent vertical wall of the case is the left hand foul territory of the field and may comprise an inner portion 42 that slopes toward the adjacent portion of the runway 10 and the home base 17 and an outer portion 43 that slopes toward the channel 23.

The corner portion of the case nearest to the batter's box is severed from the remainder of the case along a vertical plane and is attached to one vertical wall of the case by 80 hinges 44, as shown in Figures 1 and 5 and thus defines a door that is angular in cross sectional contour and is adapted when closed to cover the opening resulting from the separation of said corner portion, indicated 85 at 45, from the remainder of the case. The floor of the batter's box is extended as indicated at 46 to provide a floor for the space between the extensions 13^a at the rear of the back stop 12, said space being indicated at 90 47 in Figure 5 and being closed at its rearward end by a vertical wall 48 which spans the space between adjacent vertical walls of the case. The "bat" or striking member 49 is supported at its upper end, as at 50 in the upper end portion of a substantially rectangular opening 51 in the middle portion of the back stop 12 to swing forwardly and upwardly about a horizontal axis.

Bumpers, as at 52, at the lower end of the opening 51 limit the swinging movement of the striking member 49 in a rearward direction so that the striking member 49 is not permitted to swing rearwardly to vertical position but will be inclined slightly to the perpendicular when in rearwardly swung position. The mechanism for actuating the "bat" or striking member 49 and for controlling the movements of the latter is housed within the space 47 and includes a 100 carrying block 53 which is pivotally attached at 54 to a supporting block 55 within the space 47. The carrying block 53 is swingable vertically but normally is maintained by gravity upon the block 55 so that a latch plate 56 which is secured to the forward side of the block 53 and extends below the level of the latter at the forward end of the supporting block 55 will engage with the upturned rearward end portion 57 of a rearwardly and downwardly extending bracket arm 58 on the lower end portion of the striking member 49, whereby the striking member normally will be maintained in its rearwardly swung or "set" position. A horizontal rock shaft 59 is journaled in the arms of a bracket 60 attached to the upper portion of the striking member 49 and is integral with the rearward arm 61 of a pendant substantially U-shaped trigger 62. The 110

rearward arm of the trigger 62 is continuously in contact with the forward edge of a forwardly and downwardly turned extension or upper end portion 63 of the latch plate 56. The web of the trigger 62 extends through a vertical slot 64 in the striking member 49 so that the forward arm of the trigger, indicated at 65, normally will be maintained in front of the striking member 49 as a result of the action of the downwardly actuated latch plate on the trigger. However, a blow on the forward arm 65 of the trigger from a point at the front of the striking member will cause the trigger to swing rearwardly in the slot 64 about the axis of the rock shaft 59 and the latch plate 56 and block 53 will be pushed upwardly and rearwardly by the rearwardly swinging trigger, thereby disengaging the latch plate 56 from the upturned rearward end portion 57 of the bracket arm 58 and releasing the striking member 49. It is to be observed at this point that the latch plate 56 may be maintained normally in position to engage 25 with the upturned rearward end portion 57 of the bracket arm 58 not only because of the action of gravity but because of the action of an expansion spring 66 which reacts at its forward end against the rearward face 30 of the block 53 and at its rearward end against the block 67 at the rear of the supporting block 55. The block 67 has the upper surface thereof inclined, as clearly shown in Fig. 5 and carries an arched rest plate 68 over which extends the rearward end portion of a spring bar 69. The extreme rearward end portion of the spring bar 69, rearwardly of the rest plate 68, is provided with a slot 70 for the reception of a screw 71 which is secured in the block 67. A portion 40 of the spring bar 69 which is located forwardly of the rest plate 68 is slotted as indicated at 72 and is retained against the upper face of the block 67 by a clamping plate 73 and a screw 74 which extends through an opening in the clamping plate and through the slot 72 into the block 67. The spring bar 69 is bent downwardly and rearwardly adjacent to its forward end at 75 and then 45 forwardly and upwardly at 76 to provide a socket for the reception of a horizontal bar 77 which has forwardly turned end portions 78 secured at 79 to the striking member 49. The spring 69 is normally under stress when 50 the striking member 49 is in its rearwardly swung position because of the engagement of the bar 77 with the forward end portion of the spring bar and therefore when the striking member 49 is released from the 55 latch plate 56, the spring bar 69 will act to impel the striking member 49 forwardly and upwardly at high velocity.

The striking member 49 also is provided with vertical slots 80 and 81 respectively 60 which flank the slot 64 and through which two triggers 82 respectively extend. The triggers 82 are integral with pendant arms 83 on aligned horizontal rock shafts 84 which are journaled in brackets 85. The brackets 85 are secured to the striking member 49 below the level of the bracket 60. Rearwardly extending rocker arms 86 at the outer ends of the rocker arms 84 are connected by a horizontal bar 87. A tension spring 88 is attached at its upper end to the bar 87 and at its lower end to the floor 46 and tends to maintain the triggers 82 forwardly of the plane of the front face of the striking member. The impact of a blow on either one of the triggers 82 will cause upward swinging movement of the bar 87 against the action of the spring 88. A horizontal rock shaft 89 which is journaled in bearings 90 secured to the back stop 12 is integral with a rocker arm 91 which rests upon the bar 87. The rock shaft 89 also carries a rocker arm 92 which inclines downwardly and rearwardly from its junction with the rock shaft 89 and has limited swinging movement between cooperating stops 93 and 94 respectively which are carried by the back stop 12. The lower end portion of the rocker arm 92 is formed as clearly shown in Figure 5 to serve as a clapper, indicated at 95, for engaging with a bell 96 which is secured on the floor 46, whereby an audible signal will be given when either one of the triggers 82 is pressed or forced rearwardly from its normal position into its slot in the striking member 49.

The pitching mechanism is illustrated to advantage in Figures 6 and 7 and comprises a throwing arm 97 supported on a shaft 98 which extends between and has the opposite end portions thereof supported in aligned openings in the side members 99 of a frame which is indicated generally at 100. The side members 99 of the frame are connected to each other at their opposite ends by cross members 101 and 102, respectively. A torsion spring 103 encircles the shaft 98 and is attached at one end to the arm 97 intermediate the length of the latter and at its opposite end to a ratchet wheel 104. The ratchet wheel 104 is loose on the shaft 98 but is held against rotation in one direction about the axis of the shaft 98 by the engagement of a spring finger 105 with the teeth of the ratchet wheel, the spring finger being rigidly secured at one of its ends by screws 106 to the cross member 101. The torque which the spring 103 exerts on the arm 97 therefore can be varied within limits by rotating the ratchet wheel on the shaft to wind the spring 103 and the torque which the spring 103 exerts on the arm 97 will be maintained at a predetermined point because the engagement of the spring finger 105 with the ratchet wheel 104 normally will prevent unwinding of the spring 103. The

free end portion of the arm 97 carries a substantial cylindrical holder or cup 107 which is shown as being partially closed at its lower end by a diametrical pin 108. The 5 cup or holder is provided with a guard lip 109. As shown in Figures 1 and 3, a slot 110 extends in the infield portion of the game board midway between the channels 18 and 19 from the floor of the batter's box 10 toward second base. As shown in Figure 7, this slot is enlarged in width from its upper to its lower end. A standard 111 is upstanding from the forward end portion of a handle 112 and extends loosely through 15 the slot 110. The standard 111 is rigidly secured at its upper end to the frame 100 of the pitching mechanism so that the frame 100 will be substantially parallel to the handle 112 and the arm 97 will swing in the 20 general direction of the propelling member 49 when actuated by the spring 103. The handle 112 extends rearwardly in the space between the game board and the bottom of the case beneath and rearwardly of the 25 batting mechanism, the rearward end portion of the handle being received within the space within the angular door 45 when the latter is in closed position and being accessible when the door is open. The frame 30 100 is movably supported on the infield portion of the game board by means of a flat slide member 113 which rests flatwise upon the game board and spans the slot 110. The slide member 113 has a vertical lug 114 up- 35 standing therefrom at the approximate center of the slide member. The upper end portion of the lug 114 is provided with a horizontal opening with which the eye of an attaching member 115 that depends from 40 the frame 100 is engaged, the connection of the attaching member 115 with the frame being in the same vertical plane as the longitudinal median line of the frame, whereby the frame is permitted to rock about its longitudinal axis and also is capable of limited 45 axial movement about an axis extending substantially at right angles to the direction of length of the frame 100 and diametrically of the opening in the upper end portion of 50 the lug 114. Moreover, the connection of the frame 100 with the lug 114 being a loose pivotal connection, the frame 100 is capable of limited turning movement about an axis extending longitudinally of the lug 114. 55 A rock shaft 116 spans the side members 99 of the frame 100 forwardly of the shaft 98 and is journaled in aligned transverse openings in the side members 99. The rock shaft 116 has an offset portion 117 located 60 between the side members 99 in position to engage with a projection 118 at the extremity of the enlarged lower end portion of the arm 97 and to then hold the arm 97 against swinging from the position shown in Figure 65 6, the offset portion 117 thus constituting a swinging latch and a spring 119 which connects the offset portion 117 of the rock shaft 116 with the cross member 101 at the rear of the frame 100 functions to hold the offset portion 117 in engagement with the projection 118. The offset portion 117 of the rock shaft can be swung out of engagement with the projection 118 by rocking the shaft 116 in a clockwise direction. This may be accomplished by imparting motion to the rock shaft 116 through a rocker arm 120 which is joined to the rock shaft 116, a link 121, a rocker arm 122 of a rock shaft 123 which is journaled in a bearing 124 on the forward end of the frame 100, a rocker arm 125 70 which is joined to the rock shaft 123 and extends from the latter in a direction opposite to the rocker arm 122, and a pull rod 126 which is slidably supported in aligned openings in the guide brackets 127 which are secured to the handle 112. The pull rod 126 is formed with the rearward end portion thereof bent upwardly and then across the handle 112 to provide a substantially U-shaped thumb piece as indicated at 128. 75 The free end of this thumb piece slides in contact with a metal strip 129 which is secured to the handle 112 and has the rearward end portion thereof bent outwardly at 130 to provide a stop for engaging with the thumb piece 128 to limit the axial movement of the pull rod 126 along the handle toward the free end of the handle and in the direction required to transmit motion to the rocker arm 125 and then through the rock shaft 123, rocker arm 122, link 121, rocker arm 120 and rock shaft 116 to the offset portion or latch 117 of the rock shaft 116. As a result of such motion, the latch 117 will be 80 swung out of engagement with the projection 118 on the arm 97 and the latter will swing as a result of the action of the spring 103 in the general direction of the propelling member of the batting mechanism and until the free end portion of the arm 97 strikes a bumper 131 on the forward end portion of the frame 100. 85 90 95 100 105 110 115 120 125 130

A coil spring 132 which is attached at one end to the pull rod 126 adjacent to the forward end of the latter and at its other end to a fixed arm 133 on the forward end of the handle 112 tends to prevent axial movement of the pull rod 126 in the direction required to cause actuation of the rocker arm 125 so that positive actuation of the pull rod 126 is required to effect release of the arm 97 from the latch 117.

Each of the hereinbefore mentioned channels or grooves in the surface of the game board is transversely curved substantially along an arc of a circle so that a ball which has been placed therein will roll freely therealong. The equipment used with the game board in the playing of the game includes a set of nine balls made of steel or other rela-

tively heavy material. Each of these balls is adapted to roll along any one of the hereinbefore mentioned channels or grooves and will be hereinafter referred to as "base running" balls. These nine balls represent the nine players of a baseball team and the respective balls may be marked to indicate the positions of the ball players whom they represent. In addition, the equipment for the playing of the game comprises one or more lighter balls adapted to be placed in the cup or holder 107 on the throwing arm 97 and to be thrown from the cup by centrifugal force toward the propelling member 49 of the batting mechanism when the throwing arm 97 is swung by the action of the spring 103 forwardly and downwardly from the position shown in Figure 6. The last mentioned balls will be hereinafter referred to as the "pitching" balls and only one of such balls is used at any given time during the playing of the game. The base running balls and the pitching ball or balls may be held in a case indicated at 134 which is disposed in the foul territory of the playing field in a position corresponding to that of a player's bench in a park for the playing of an actual game of baseball. The case 134 may have a hinged lid or cover 135. Substantially U-shaped stop strips having the arms thereof flaring outward at their extremities are pivotally attached to the game board in the positions which would be occupied on a field for playing the actual game of baseball by the right fielder, the first baseman, the second baseman, the center fielder, the short stop, the right fielder, and the third baseman. The fielding stops are indicated at 136 and each is turned about its pivotal connection with the game board so that the arms thereof will face up the slope of the inclined surface on which the fielding stop is disposed so that a ball rolling down the slope is likely to lodge between the arms of the fielding stop. A substantially Y-shaped member 137 which is termed the "catcher" is positioned in the batter's box 11 with the arms or branches of the Y-shaped member at the forward end of the batter's box. The side faces of the member 137 are curved concavely longitudinally of the member and respectively are adapted to deflect a ball that may roll thereagainst into the channel 18 and into the channel 19 for a purpose to be presently described.

In the playing of the game, a base running ball is placed in the runway 10 at the right hand side of the batter's box and will be retained against movement along the runway by a stop pin 138 which is movable vertically in an opening in the bottom of the runway 10 adjacent to the right hand side of the batter's box and which normally protrudes from the opening in the bottom of the runway and prevents movement of the

base running ball along the runway toward first base. The stop 138 may be termed the batter's stop and may be actuated by means which will be presently described to move downward until flush with the bottom of the runway. The base running ball then is permitted to roll along the runway to the first base portion of the runway but normally will be prevented from further movement in the runway by a vertically movable first base stop pin 139 which protrudes from a vertical opening in the bottom of the runway adjacent to the first base portion 14. The first base stop 139 likewise can be actuated by means to be presently described and moved downward until flush with the bottom of the runway and the base running ball may then proceed along the runway to the second base portion 15 in which place it will contact with a second base stop 140 which normally protrudes from an opening in the bottom of the runway adjacent to the second base portion 15. When the second base stop 140 has been actuated to move downward until flush with the bottom of the runway, the base running ball may move along the runway to the third base portion of the runway. A third base stop 141 which normally protrudes through an opening in the runway adjacent to the third base portion 16 of the runway will prevent movement of the base running ball past third base toward the home base 17 until the third base stop 141 has been moved downward as a result of actuation by means which will be presently described until it is flush with the bottom of the runway. The base running ball then may proceed past third base along the runway 10 into the home base 17.

The batter's stop 138 is pivotally attached at its lower end to the outer end of an arm 142 which extends laterally of and is rigid with a rocker arm 143 on a rock shaft 144. The rock shaft 144 is horizontal and is journaled in aligned openings in the upper ends of brackets 145 and 146 respectively which are secured on the bottom 1 beneath the game board. A rocker arm 147 on the rock shaft 144 extends in the direction opposite to the rock shaft 143 and carries a weight 148 which serves to swing the rocker arm 147 downward against the bottom 1 and to thus elevate the stop pin 138, whereby the latter normally is maintained in its raised or operative position. The stop pin 139 is pivotally attached at its lower end to the outer end of a rocker arm 149 on a rock shaft 150. The rock shaft 150 is horizontal and is journaled in aligned openings in brackets 151 which are secured on the bottom 1. A rocker arm 152 on the rock shaft 150 extends in a direction opposite that of the rock shaft 149 and carries a weight 153 which tends to hold the rocker arm 152 against the bottom 1 and the stop pin 139 in raised or operative posi-

tion. The second base stop 140 is pivotally attached at its lower end to the outer end of a rocker arm 154 on a rock shaft 155 which is journaled in brackets 156 on the bottom 1 and has a rocker arm 157 which extends in the direction opposite that of the rocker arm 154 and carries a weight 158. The stop pin 140 therefore normally will be maintained in raised or operative position. The stop pin 141 is pivotally attached at its lower end to the outer end of a rocker arm 159 on a horizontal rock shaft 160. The rock shaft 160 is journaled in aligned openings in the upright portions of brackets 161 on the bottom 1 and has a second rocker arm 162 which carries a weight 163 and extends in the direction opposite that of the rocker arm 159 whereby the stop pin 141 normally will be maintained in raised or operative position.

20 The invention provides means operable to depress all of said stops 138, 139, 140 and 141 simultaneously. Such means includes a central motion transmitting element having the form of a rotary disk 164 mounted 25 on a vertical shaft 165 which is supported on a block 166 secured to the bottom 1. The shaft 165 is braced by a brace member 167. The rotary disk 164 is provided with five spaced radially extending arms 168, 169, 170, 171 and 172 respectively. The arm 168 is in contact with an upstanding rocker arm 173 on a horizontal rock shaft 174 which is journaled in openings in brackets 175 and 176. The rock shaft 174 has oppositely 30 extending rocker arms 177 and 178 respectively. The rocker arm 177 extends across the rocker arm 142 while the rocker arm 178 carries a weight 179 which acts to hold the upstanding rocker arm 173 in contact with 35 the radial arm 168 and tends to prevent the rocker arm 177 from exerting any pressure on the rocker arm 142.

An upstanding rocker arm 180 on the horizontal rock shaft 181 is continuously in 40 contact with the radial arm 172. The rock shaft 181 is journaled in aligned openings in brackets 182 and 183 and has oppositely extending rocker arms 184 and 185 respectively. The rocker arm 184 carries a weight 186 and the rocker arm 185 has the outer end portion thereof resting upon the rocker arm 149 but normally does not exert any pressure on the rocker arm 149 as will be understood.

55 An upstanding rock shaft 187 on a horizontal rock shaft 188 is continuously in contact with the radial arm 171. The rock shaft 188 is journaled in openings in brackets 189 and 190 on the bottom 1 and carries a laterally extending rocker arm 191 which extends underneath the rocker arm 157.

An upstanding rocker arm 192 on the horizontal rock shaft 193 is continuously in contact with the radial arm 170. The rock shaft 193 is journaled in aligned openings

in brackets 194 and 195 respectively. The brackets 194 and 195 are secured on the bottom 1 and the rock shaft 193 carries a laterally extending rocker arm 196 which extends across the rocker arm 159. A rocker 70 arm 197 extends from the rock shaft 193 in the direction opposite that of the rocker arm 196 and carries a weight 198. It will be understood that the weight 198 will act to hold the rocker arm 192 continuously in contact with the radial arm 170 and will prevent the arm 196 from exerting any pressure on the rocker arm 159 when the hereinbefore described motion transmitting elements are in a position of rest. It will be manifest from the foregoing that the respective stops 138, 139, 140 and 141 will be depressed simultaneously as a result of motion transmitted thereto when the disk 164 is turned in a clockwise direction about the 85 axis of the vertical shaft 165, from the position shown in Figure 8 and that the respective stops will return instantly to raised or active positions as soon as the torque on the disk 164, tending to turn the disk 164 from the position shown in Figure 8, is removed. The invention provides means acting automatically to turn the disk 164 from the position shown in Figure 8 to effect lowering of the respective stops from operative 90 positions when the propelling member 49 of the batting mechanism swings from set or rearwardly swung position. Such means comprises an upstanding rocker arm 199 on a horizontal rock shaft 200 which is journaled in aligned openings in brackets 201 and 202 respectively. The rock shaft 200 extends rearwardly in the space between the bottom 1 and the game board and is provided beneath the floor 46 of the space 47 100 with oppositely extending rocker arms 203 and 204 respectively. The rocker arm 203 carries a weight 205 while the rocker arm 204 has a laterally turned end portion indicated at 206 which extends underneath the 110 laterally turned lower end portion 207 of a substantially vertical push rod which comprises a lower section 208 which is slidable in the vertical opening in a horizontal arm at the upper end of a guide bracket 209 and an upper section 210 which is pivotally attached at its lower end to the upper end of the section 208 and is pivotally attached at its upper end to the outer end of the rocker arm 211 and the rock shaft 212. The section 208 of the vertical push rod extends through an opening in the floor 46 as best seen in Figure 3. The rock shaft 212 is journaled in aligned horizontal openings in upstanding arms or brackets 213 and 214 respectively which are secured on the floor 46. The rock shaft 212 has a downwardly offset and laterally turned intermediate portion 215 to which is attached one end of a retractile spring 216 having the other end thereof 115 120 125 130

attached to the back stop 12. The rock shaft 212 is provided with a rocker arm 217 which extends parallel to the rocker arm 207 underneath the rod 77 (see Fig. 5). The spring 216 acts to rock the shaft 212 to maintain the rocker arm 217 continuously in contact with the rod 77 although a weight 218 on the rocker arm 211 substantially balances the action of the spring 216. The upper section 210 of the substantially vertical push rod is held against any appreciable lateral movement by a guide 219 with which the upper section 210 is in sliding contact. When the propelling member 49 of the batting mechanism is released from the latch plate 56, it is swung forward and upward and the rod 77 is swung downward and forward, thereby swinging the rock shaft 217 downward and causing a like movement of the rock shaft 211 against the action of the spring 216. The downward movement of the outer end of the rock shaft 211 causes downward movement of the push rod 210—208 whereby the rocker arm 204 will be swung downward and the rock shaft 200 will be rocked in a counter-clockwise direction which will cause swinging of the upstanding rocker arm 199 in contact with the radial arm 169 in the direction required to cause turning of the disk 164 in a clockwise direction from the position shown in Figure 8, whereby the respective stops 138, 139, 140 and 141 will be depressed simultaneously when the propelling member 49 of the batting mechanism swings forward and upward from "set" position. The invention also provides means other than that which has just been described for actuating the disk 164 to cause depression of all of said stops 138, 139, 140 and 141 simultaneously. The last named actuating means comprises a rock shaft 220 which extends in the space between the bottom 1 and the game board nearly to the centerfield portion of the game board and is journaled in aligned horizontal openings in upstanding arms of brackets 221, 222 and 223 respectively. These brackets are secured on the bottom 1. An upstanding rocker arm 224 at the inner end of the rock shaft 220 is in contact continuously with the radial arm 172 on the disk 164. The rock shaft 220 is provided at its outer end with oppositely extending rocker arms 225 and 226 respectively, the rocker arm 225 carrying a weight 227 which acts to hold the rocker arm 226 raised from the bottom 1 of the case and the upstanding rocker arm 224 in contact with the radial arm 172 on the disk 164. The outer portion 28 of the right hand section of the centerfield portion of the game board is provided with a slot or aperture 228 adjacent to the extreme outer end of the channel 22. A rock shaft 229 extends transversely of the aperture 228 at the end of the latter nearest to the division plate 24 and carries a rocker plate 230 which substantially fills the aperture 228 and is rigid with the rock shaft 229. The rock shaft 229 has a laterally turned rocker arm 231 which carries a weight 232. The outer end portion of the rocker arm 226 is curved laterally and extends across the free end portion of the rocker arm 231. The arrangement is such that when the free end portion of the rocker plate 230 is depressed, the free end portion of the rocker arm 231 will be raised and the rocker arm 226 will be raised also, thus aiding the weighted rocker arm 225 in turning the rock shaft 220 in the direction required to transmit motion through the upturned rocker arm 224 to the radial arm 172 so that the disk 164 will be rotated in a clockwise direction and the respective stops 138, 139, 140 and 141 will be depressed.

In addition to the hereinbefore described means for actuating the stops 138, 139, 140 and 141 simultaneously, the invention provides means for actuating the respective stops 139, 140 and 141 independently of one another.

The means for depressing the first base stop 139 independently of the other stops comprises a horizontal rock shaft 233 journaled in aligned openings in vertical arms of brackets 234 and extending within the space between the game board and the bottom 1 from the infield to the left hand section of centerfield. The rock shaft 233 is provided at its inner end with oppositely extending rocker arms 235 and 236 respectively, the rocker arm 235 carrying a weight 237 and the rocker arm 236 having the outer end portion thereof curved laterally and arranged to extend across the rocker arm 149. The rock shaft 233 is provided at its outer end with a rocker arm 238 which extends laterally of the rock shaft 233 at the same side of the latter as the rocker arm 236. The outer end portion of the rocker arm 238 is bent laterally of said rocker arm as indicated at 239 in Figure 10. A rock shaft 240 is journaled in aligned openings in the bracket 241 which is positioned beneath the channel 34. The rock shaft 240 has a lateral arm 242 extending across the laterally turned end portion 239 of the rocker arm 238 and has a rocker arm 243 extending in the direction opposite the arm 242. The rock shaft 240 also has a control member or lever in the form of a rocker arm 244 which extends laterally of the same side of the rock shaft 240 as the arm 242 and has an inclined presser portion 245 arranged to extend through a slot 246 in the bottom wall of the channel 234 adjacent to the outer end of the latter. The rocker arm 243 carries a weight 247 which acts to raise the presser portion 245 of the control member to position to protrude from the slot 246 in the channel 34. When the presser portion 245 of the

control member is depressed in the slot 246, the rocker arm 242 will be forced downward in contact with the laterally turned end portion 239 of the rocker arm 238 and will cause the rock shaft 233 to rock against the action of the weight 237, whereby the rocker arm 236 will be swung downward in contact with the rocker arm 149 and will depress the first base.

10 A means for depressing the first base stop 139 independently of the remaining stops is illustrated in Figure 9 and comprises a horizontal rock shaft 248 journaled in aligned horizontal openings in vertical arms 15 of brackets 249 which are positioned beneath the infield portion of the game board. The rock shaft 249 is provided at its opposite ends with rocker arms 250 and 251 respectively, both extending at the same side of the 20 rock shaft. The rocker arm 250 extends across the rocker arm 149 while the rocker arm 251 extends underneath the rocker arm 252 on a rock shaft 253 which is journaled in aligned horizontal openings in the arms 25 of a bracket 254. A rocker arm 248^a extends from the rock shaft 249 oppositely to the arms 250 and 251 and carries a weight 248^b. The rock shaft 253 has a rocker arm 255 extending in a direction opposite the rocker arm 252 and carrying a weight 256. A control member for rocking the shaft 253 is in the form of a rocker arm 257 extending laterally of the same side of a rock shaft 253 as the rocker arm 252 and having a raised 35 inclined presser portion 258 projecting through a slot 259 in the bottom of the channel 18. It therefore will be manifest that when the presser portion 258 of the control member 257 is depressed in the slot 259, the rocker arm 252 will be swung downward and will carry the rocker arm 251 downward, thus causing the first base stop 139 to be depressed.

40 A means for depressing the second base stop 140 independently of the remaining stops also is illustrated in Figure 9 and comprises a horizontal rock shaft 260 journaled in aligned openings in brackets 261 and having a laterally turned rocker arm 50 262 at one end thereof. The rock shaft 260 has oppositely extending rocker arms 263 and 264 respectively. The rocker arm 263 carries a weight 265 while the rocker arm 264 extends laterally of the same side of 55 the rock shaft 260 of the rocker arm 262 and has a laterally turned end portion 266 extending across the rocker arm 154. A control member in the form of a rocker arm 267 on a rock shaft 268 is journaled in aligned horizontal 60 openings in the arms of the brackets 269 which are located beneath the portion of the runway 10 between first base and second base. Intermediate portion of the control member 267 is arched to provide a presser portion 270 which protrudes within the run-

way from a slot 271 in the bottom of the portion of the runway 10 between first base and second base. The free end portion of the control member 267 extends across the outer end portion of the rocker arm 262. 70 The rock shaft 268 carries a rocker arm 272 which extends from the rock shaft in a direction opposite to that of the control member 267 and carries a weight 273, whereby the arched portion 270 of the control member, which also is inclined as shown, normally is maintained in raised position. It is obvious that depression of the control member will cause the rocker arm 262 to be swung downward, thereby rocking the shaft 80 260 and causing the rocker arm 264 to swing downward and to impart like motion to the rocker arm 254, whereby the second base stop 140 will be depressed.

85 Figure 9 also illustrates an additional means for depressing the second base stop 140 independently of the remaining stops which comprises a rock shaft 274 which is journaled in aligned horizontal openings in brackets 275 and is provided at one end with 90 oppositely extending lateral rocker arms 276 and 277 respectively, the rocker arm 276 extending across the rocker arm 154 and the rocker arm 277 carrying a weight 278. The rock shaft 274 is provided at its other end 95 with a laterally extending rocker arm 279 which extends oppositely of the same side of the rock shaft 274 as the rocker arm 278. The rock shaft 274 is provided at its other end with a laterally extending rocker arm 100 279 which extends to the same side of the rock shaft 274 as the rocker arm 276. The rocker arm 280 on a rock shaft 281 which is journaled in aligned horizontal openings in brackets 282 extends across the rocker arm 105 279. A rock shaft 281 also is provided with a rocker arm 283 extending laterally of the rock shaft 281 in the side of the latter opposite the rocker arm 280 and carrying a weight 284. The rock shaft 281 also has a 110 rocker arm 285 which extends laterally of the same side of the rock shaft 281 as the rocker arm 280. A control member in the form of a rocker arm 286 on a horizontal rock shaft 287 which is journaled in aligned 115 horizontal openings in the arms of a bracket 288 has an upwardly offset intermediate portion 289 which extends through a slot 290 in the bottom of the portion of the runway 10 which extends between third base 16 and the home base 17. The portion 289 of the control member 286 is inclined as shown and constitutes a presser member. The free end portion of the control member 286 is bent laterally as indicated at 291 and rests upon the outer end portion of the rocker arm 285. A weight 292 on a rocker arm 293 which extends from the rock shaft 287 in the direction opposite that of the control member 286 tends to hold the presser portion 289 125 130

in raised position. It is obvious that when the presser portion 289 is depressed, motion will be transmitted through the rocker arm 285, rock shaft 281, rocker arm 289, rocker arm 279, rock shaft 274, and rocker arm 276 to the rocker arm 154, which will be swung downward, thereby depressing the second base stop 140. As best seen in Figures 9 and 10 considered together and as also illustrated in Figure 2, the invention provides still other means for depressing the second base stop 140 independently of the remaining stop. Such additional means comprises a horizontal rock shaft 294 which extends beneath the left field portion of the game board and is journaled in aligned openings in brackets 295.

The rock shaft 294 is provided at its inner end with oppositely extending rocker arms 296 and 297 respectively, the rocker arm 296 carrying a weight 298 and the rocker arm 297 extending across the rocker arm 279. The rock shaft 294 is provided at its outer end with a rocker arm 299 which extends laterally of the same side of the rock shaft 294 as the rocker arm 297 and has the outer end portion thereof turned laterally as indicated at 300. A control member in the form of a rocker member 301 and a rock shaft 302 which is journaled in aligned openings in the vertical arm of the bracket 303 has an upwardly offset intermediate portion 304 protruding from a slot 305 in the bottom of the outer end portion of the channel 38. The free end portion of the control member 301 is bent laterally as indicated at 306 and extends across the free end portion 300 of the rocker arm 299. The raised intermediate portion 304 of the control member constitutes a presser member which is inclined downwardly toward the outer end of the channel 38 as shown. A rocker arm 307 extends from the rock shaft 302 in a direction opposite the control member 301 and carries a weight 308. When the presser portion 304 of the control member is depressed in the slot 305 motion will be transmitted to the rocker arm 299, rock shaft 294, rocker arm 297, rocker arm 279, rock shaft 274 and rocker arm 276 which will cause the second base stop 140 to be depressed.

As illustrated in Figure 9, the invention provides means for depressing the third base stop 141 independently of the remaining stops which comprises a rock shaft 309 journaled in aligned horizontal openings in the upper ends of vertical arms of brackets 310. The rock shaft 309 has oppositely extending rocker arms 311 and 312 respectively extending in opposite directions from opposite ends of the rock shaft. The rocker arm 311 carries a weight 313 and is arranged with the free end portion thereof extended underneath the rocker arm 162. The rocker

arm 312 is bent upwardly adjacent to its outer end as indicated at 314 to extend slidably through an opening in the game board at the junction of the channels 19 and 20. The opening in the game board through which the upturned end portion 314 extends is in the form of a slot, as best seen at 315 in Figure 1 and the upper end portion of said rocker arm is bent laterally across the channel 19 and then back upon itself as indicated at 316 to provide a stop, the free end portion of the part 316 being curved as indicated at 317 to extend across the outer end of the channel 20. The rocker member comprises the parts 317, 316, 314 and 312 and constitutes a control member adapted to be actuated to rock the shaft 309 when the parts 314 are swung outwardly in the slot 315 as because of the impact of a ball which is rolled down the channel 19 against stop 316. The parts 316 and 317 also will act to deflect a ball which is rolled down the channel 19 against the stop 316 into the channel 20. The part 314 of the rocker member will swing downwardly as well as outwardly in the stop 315, thereby rocking the shaft 309 and causing the rocker arm 311 to swing upwardly. This upward movement of the rocker arm 311 will cause upward movement of the rocker arm 162, thereby locking the shaft 160 and causing the rocker arm 159 to swing downward. The downward movement of the rocker arm 159 of course will cause the third base stop 141 to be depressed.

The invention provides other means for depressing the third base stop 141 independently of the remaining stops. Such additional means is illustrated in Figure 4 and comprises a rock shaft 318 which is journaled in aligned horizontal openings in the upper end portions of vertical arms of brackets 319. The rock shaft 318 has oppositely extending rocker arms 320 and 321 respectively at one of its ends, the rocker arm 320 carrying a weight 322 and the rocker arm 321 having a laterally turned end portion extending across the rocker arm 159. A control member is in the form of a rocker arm 323 extending laterally of the rock shaft 324 which is journaled in aligned horizontal openings of a bracket 325 which is positioned beneath the portion of the runway 10 that extends between second base and third base. The intermediate portion of the control member 323 is upwardly offset as indicated at 326 and protrudes from a slot 327 in the bottom of the portion of the runway 10 between second base and third base. The free end portion of the control member 323 extends across a rocker arm 328 on the rock shaft 318, the rocker arm 328 extending laterally of the same side of the rock shaft 318 as the rocker arm 321. A rocker arm 329 which extends from the rock shaft 324 in the direction opposite that of the rocker arm

323 carries a weight 330. The raised intermediate portion 326 of the control member 323 is inclined downwardly toward the second base portion of the runway and constitutes a presser member which is adapted to be depressed in the slot 327 and to then transmit motion through the rocker arm 328, rock shaft 318, rocker arm 321 and rocker arm 159 to the third base stop 141, whereby the third base stop will be depressed.

From the foregoing description of the various parts of the device, the operation thereof may be readily understood. The game may be played by two people or by two teams. The score may be kept on a card as in the actual game of baseball. A base running ball is placed in the runway 10 between the stop 138 and the adjacent side of the batter's box. The pitching ball is placed in the cup or holder 107, the throwing arm 97 of the pitching mechanism is swung to "set" position, and the handle 112 then is grasped and is manipulated until the pitching mechanism is in a desired position with respect to the propelling member 49 of the batting mechanism. The thumb piece 128 then is manipulated to release the arm 97 from the latch 117. The spring 103 then acts to swing the arm 97 in the general direction of the propelling member 49 of the batting mechanism and the pitching ball will be ejected from the holder 107 by centrifugal force and will be thrown toward the propelling member 49 of the batting mechanism. The trajectory of the thrown ball of course will vary with the position of the pitching mechanism on the game board and the skill of the manipulator of the handle 112 thus is called into play to the end that the thrown ball may be thrown as required to cause or tend to cause a desired result. For example, should the ball hit one of the triggers 82, the propelling member 49 will not be released from the latch plate 56 but the bell 96 will be sounded to indicate a strike on the batter. If the ball should strike the propelling member 49 or the back-stop 12 without hitting the triggers 82 or 65, the result counts as a "ball". Therefore, the batter may be retired on "strikes" as a result of skillful manipulation of the pitching mechanism or may be given a "base on balls" as a result of unskillful manipulation of the pitching mechanism. When the trigger 65 is struck with a ball, the propelling member 49 will be released from the latch plate 56 and will be actuated by the spring 69 to project the ball onto the playing field. The surfaces of the various portions of the playing field are inclined according to a definite plan so that the course which the pitching ball will take after striking the field surface will vary with the position at which the ball lands on the field surface. The respective stops 138, 139, 140

and 141 will be depressed coincidentally with the swinging of the propelling member 49 to project the pitching ball onto the field and any base running ball or balls on the runways 10 then may advance along the runway. It will be observed that the propelling member 49 has the front face thereof convexly curved transversely thereof and the direction which the pitching ball takes on striking the propelling member 49 and the trigger 65 may be determined by the player who is manipulating the pitching mechanism by causing the pitching ball to strike the propelling member 49 and the trigger 65 laterally of one side or the other of the vertical median line of the propelling member. The pitching mechanism may be manipulated so that the pitching ball will be projected by the propelling member 49 onto the surface of the right field and the pitching ball then will roll down the inclined right field surface to the channel 21 and along the latter to the first base portion 14 of the runway 10. Should the pitching ball reach first base before the base running ball which has been retained against movement along the runway 10 by the stop 138 until the propelling member 49 was actuated, the base running ball will be considered as having been "put out" as in the case of the actual game of baseball. Should the pitching ball after striking the propelling member 49 or the back stop without actuating the trigger 65 be deflected by the catching member 137 into the channel 18, the ball will strike the presser portion 258 of the control member 257 and will depress stop 139 so that base running ball on first base may advance along the runway 10. The pitching ball will roll down the channel 18 to second base and should it reach second base before the base running ball that was on first base, the latter will be "put out". Should the pitching ball be deflected from the batter's box into the channel 19, it will on striking the portion 316 of the control member 312 be deflected into the channel 20 and at the same time will actuate the control member 312 to cause the third base stop 141 to be depressed and a base running ball that was on third base then may roll along the runway toward the home base 17. The race then is between the pitching ball moving along the channel 20 and the base running ball which is on third base. Should the pitching ball reach the home base 17 before the base running ball, the latter has been "put out" while should the base running ball reach the home base first, a "run" is scored. From the foregoing, it will be understood that a "put out" will be made when the pitching ball reaches a base in advance of the base running ball. The space between the arms of each of the fielding strips 136 may be considered a pocket in which the

pitching ball will lodge should it roll between the arms of the fielding strip after striking the inclined field surface adjacent to the fielding strip. A "put out" also is scored 5 when the pitching ball lodges in the pocket provided by any one of the fielding strips or in the cup of the pitching mechanism. A base running ball passing along the runway from first base to second base will depress 10 the presser portion 270 of the control member 267 so that the second base stop 140 will be depressed to permit the advance of any base running ball which happens to be on second base at that time. The last named 15 base running ball in passing along the runway between second base and third base will actuate the presser portion 326 of the control member 323 thus depressing the stop 141 so that a base running ball on third base 20 will proceed along the runway 10 toward the home base 17. The base running ball rolling along the runway 10 from third base toward home base will depress the portion 289 of the control member 286 and thus will cause 25 the second base stop 140 to be depressed. The pitching ball if projected to the extreme outer portion of the centerfield will roll onto the presser plate 230 and will cause all the stops 138, 139, 140 and 141 to be depressed and to remain depressed until all 30 base running balls on the runway have reached the home base, after which the pitching ball is removed by hand from the presser plate 230 when the "home run" is 35 completed. Guard plates 331 limit the entrance to the surface of the presser plate 230 to a relatively narrow opening so that the pitching ball is "batted" onto the presser plate infrequently.

40 In actual practice, it has been found that the pitching ball will be projected onto the presser plate 230 during the playing of a game of baseball with the apparatus about as often as "home runs" will be made during 45 the playing of the actual game of baseball. Should the pitching ball strike the outer portion of the left hand section of the centerfield, it may roll to the channel 34 and actuate the control member 244, which will 50 cause the first base stop 139 to be depressed and will permit the base running ball on first base, if any, to proceed along the runway to second base. The race then will be 55 between the pitching ball which will move from the channel 34 into the channel 22 and along the latter toward second base and the base running ball which moves from first base toward second base. Should the pitching ball strike the outer portion of 60 the left field on being projected onto the field surface by the propelling mechanism 49, it may move along the channel 38 and actuate the control member 301 which will cause the second base stop 140 to be depressed and the 65 race then is between the pitching ball mov-

ing along the channels 38 and 23 toward third base and the base running ball that was on second base and is permitted by the depression of the stop member 140 to move along the runway 10 toward third base. A "run" is made when the base running ball has made a complete circuit of the bases and has arrived at the home base without having been "put out" in any one of the ways which have been set out in the foregoing. The 75 stops 138, 139, 140 and 141 return instantly to raised or operative position after having been depressed as a result of the actuation of any one of the several control members except in case of a "home run" the control 80 plate 230 and as previously stated, the stops will remain depressed so long as the control plate 230 remains depressed by the weight of the pitching ball thereon.

It will be apparent from the foregoing 85 that the outcome of the game will be determined not only by chance but also by the skill of the players in manipulating the pitching mechanism. It also will be manifest that the same situations will arise in the 90 playing of a game with the apparatus as in the playing of the actual game of baseball. The outcome of the game will be in doubt until the final play has been made as in the case of the actual game of baseball. The 95 game apparatus therefore provides a wholesome means for affording entertainment and amusement to both adults and more youthful persons.

Obviously, my invention is susceptible of 100 embodiment in forms other than that illustrated in the accompanying drawings and I therefore consider as my own all such modifications and adaptations of the form of the device herein described as fairly fall within 105 the scope of the appended claims.

For example, it may be possible to apply 110 magnetism or electricity, by contact, to the various levers employed in the mechanism to produce movements.

I claim:

1. In a game apparatus of the character described, a box-like case substantially rectangular in horizontal sectional contour, said case having a removable cover, a game board fitting in said case and located between the planes of the upper and lower ends of the case, said game board being formed to provide an infield, an outerfield, and a runway dividing the infield from the outer field, the 115 portions of the side walls of the case which extend above the game board providing a fence for the outerfield and a space being provided within the case between the game board and the bottom of the case, a corner portion of said case being separate from the body of the case and hinged to the body of the case to permit access to the space within, said case between said game board and the 120 bottom of the case.

2. In a game apparatus, a game board formed to provide an infield, an outerfield, and a runway dividing the infield from the outerfield, a spring impelled batting mechanism at the head of the infield, said outerfield having means for guiding a batted ball toward said runway, and a pitching mechanism slidably supported on the infield and operable to throw a ball toward said batting mechanism.

3. In a game apparatus, a game board formed to provide an infield, an outerfield, and a runway dividing the infield from the outerfield, a spring impelled batting mechanism at the head of the infield, said outerfield having means for guiding a batted ball toward said runway, a pitching mechanism slidably supported on the infield and operable to throw a ball toward said batting mechanism, said pitching mechanism being capable of limited movement on the infield surface of the game board toward and away from the batting mechanism and being capable of limited vertical and horizontal movements independently of the game board.

4. In a game apparatus of the character described, a game board formed to provide an infield, an outerfield and a channel runway dividing the infield from the outerfield, said infield being substantially diamond-shaped in outline, a batting mechanism in one corner of the infield, and channels extending in the outerfield from the remaining corner portions of the infield for conducting batted balls from the outerfield to said runway, certain portions of said outerfield also sloping toward the adjacent channels in the outerfield, said outerfield having oppositely sloping portions with a division member between adjacent oppositely sloping portions.

5. In a game apparatus of the character described, a game board formed to provide an infield, an outerfield and a runway dividing the infield from the outerfield, and division fins extending on the outerfield from the runway to the marginal edge of the outerfield, the portions of the outerfield on opposite sides of each division fin sloping oppositely from said division fin.

6. In a game apparatus of the character described, a game board formed to provide an infield, an outerfield and a channel runway dividing the infield from the outerfield, a batting mechanism on the game board at one corner of the infield, said game board having channels leading from the remaining corners of the infield across the outerfield and said outerfield sloping toward said first named channel runway and having portions sloping toward the second named channels, and fielding elements on said game board in position to stop batted balls rolling on said portions of the outerfield toward said channels.

7. In a game apparatus of the character

described, a game board formed to provide an infield, an outerfield and a channel runway dividing the infield from the outerfield, a batting mechanism on the game board at one corner of the infield, said game board having channels leading from the remaining corners of the infield across the outerfield and said outerfield sloping toward said first named channel runway and having portions sloping toward the second named channels, 75 fielding elements on said game board in position to stop batted balls rolling on said portions of the outerfield toward said channels, said fielding elements having pockets in which said batted balls may lodge. 80

8. In a game apparatus of the character described, a game board formed to provide an infield, an outerfield and a channel runway dividing the infield from the outerfield, a batting mechanism on the game board at 85 one corner of the infield, said game board having channels leading from the remaining corners of the infield across the outerfield and said outerfield sloping toward said first named channel runway and having portions 90 sloping toward the second named channels, fielding elements on said game board in position to stop batted balls rolling on said portions of the outerfield toward said channels, said fielding elements having pockets 95 in which said batted balls may lodge, and being pivotally attached to said game board whereby said fielding elements may be turned on the game board to vary the positions on the game board of the entrances to 100 said pockets.

9. In a game apparatus of the character described, a game board having a channel runway formed with base portions at intervals along its length, and a displaceable stop member in said runway between adjacent base portions, said stops normally preventing a ball from rolling along said runway between said adjacent base portions, means for displacing said stop from its normal position in said runway to permit movement of said ball along said runway between said adjacent base portions, said stop displacing means being adapted to be actuated by a 110 batted ball. 115

10. In a game apparatus of the character described, a game board having a channel runway, a plurality of spaced stops, each normally preventing a ball from rolling in the runway past a stop, means operable to displace all of said stops from the runway to clear the runway, and other means operable to displace certain of said stops from the runway. 120

11. In a game apparatus of the character described, a game board having a channel runway, a plurality of spaced stops, each normally preventing a ball from rolling in the runway past a stop, means operable to displace all of said stops from the runway 125 130

- to clear the runway, and other means operable to displace certain of said stops from the runway, said stop displacing means being adapted to be actuated by a batted ball.
- 5 12. In a game apparatus, a game board having a channel runway formed at intervals along its length to provide base portions, stop members normally disposed in said runway between adjacent base portions 10 for preventing balls from rolling along said runway between adjacent base portions, each of said stop members being movable vertically from normal position to clear the portion of the runway in which it is disposed, 15 a plurality of control members respectively disposed at a plurality of points on said game board, and motion transmission means connecting one of said control members with all of said stops, and each of the 20 remaining control members with a particular stop, each of said control members being adapted to be actuated by the weight of a batted ball to cause movement of the stop or stops with which it is connected 25 from ball obstructing position in said runway.
13. In a game apparatus of the character described, a channel runway including a plurality of spaced bases, stops adjacent 30 to the bases and adapted when in operative position to block said runway, means operable to move said stops simultaneously from operative positions, and other means operable to move certain of said stops from operative positions independently of the remaining stops.
14. In a baseball game apparatus, a game board having a runway along which a ball may roll and including a series of spaced 40 bases, a stop adjacent to each base, each stop normally preventing movement of said ball along said runway past the base which is adjacent to that stop, a batting mechanism including a swingable propelling member, 45 and motion transmitting means operable by the swinging of said propelling member to move all of said stops to positions to permit movement of a ball along the runway past any one of said bases.
- 50 15. In a baseball apparatus, a game board having a runway along which a ball may roll and including a series of spaced bases, a stop adjacent to each base, each stop normally preventing movement of said ball 55 along said runway past the base which is adjacent to that stop, a depressible control member adapted to be depressed by the weight of a ball moving on the game board, and motion transmitting means connecting 60 said control member with said stops, whereby when said control member is depressed said stops will be moved to positions to permit movement of a ball along said runway past any one of said bases.
16. In a game apparatus of the character 65 described, a game board having a channel runway including a series of bases, a stop adjacent to each base and normally preventing movement of a ball along the runway past that base, control members protruding 70 above slots in the bottom of the runway between adjacent bases, and each adapted to be depressed by the weight of a ball passing along the runway across said control member, and a motion transmitting means connecting 75 each control member with one of said stops whereby when that control member is depressed the stop with which the control member is connected will be moved from ball-obstructing position in the runway.
17. In a game apparatus of the character described, a game board having a channel runway including a series of bases, a stop adjacent to each base and normally preventing 80 movement of a ball along the runway past that base, said game board having other channels for guiding balls into said first named channel, and motion transmitting means for moving said stops from ball obstructing 85 positions, said motion transmitting means including control members protruding from slots in the bottoms of said second named channels and each adapted to be actuated by a ball passing thereover in the 90 runway in which the control member protrudes to cause movement of a particular stop from ball obstructing position in said first named channel.
18. In a baseball game apparatus, a batter's box, a channel runway defining a diamond shaped infield and terminating at one end at the right hand side of said batter's box and at the other end at the left hand side of the batter's box, stop members located at intervals along the runway and movable to and from position to obstruct 100 said runway against the passage of a ball therealong, a second channel runway extending across said infield from the batter's 105 box to the first named runway and sloping toward the latter, said last named channel runway having a slot in the bottom thereof, a control member normally protruding 110 through said slot and adapted to be depressed by a ball rolling along the second named runway, and motion transmitting means connecting said control member with certain of said stops, whereby said certain 115 stops will be moved out of ball obstructing 120 positions in the runway when said control member is depressed.
19. In a baseball game apparatus, a batter's box, a channel runway defining a diamond shaped infield and terminating at one end at the right hand side of said batter's box and at the other end at the left hand side of the batter's box, stop members located 125 at intervals along the runway and movable to and from position to obstruct said runway against the passage of a ball therealong, a second channel runway extending across said infield from the batter's box to the first named runway and sloping toward the latter, said last named channel runway having a slot in the bottom thereof, a control member normally protruding through said slot and adapted to be depressed by a ball rolling along the second named runway, and motion transmitting means connecting said control member with certain of said stops, whereby said certain stops will be moved out of ball obstructing positions in the runway when said control member is depressed.

cated at intervals along the runway and movable to and from position to obstruct said runway against the passage of a ball therealong, a second channel runway extending 5 across said infield from the batter's box to the first named runway and sloping toward the latter, said last named channel runway having a slot in the bottom thereof, a control member normally protruding through 10 said slot and adapted to be depressed by a ball rolling along the second named runway, motion transmitting means connecting said control member with certain of said stops, whereby said certain stops will be moved out 15 of ball obstructing positions in the runway when said control member is depressed, and means in the batter's box for deflecting a ball falling onto the batter's box into said second named channel runway.

20 20. In a game apparatus of the character described, a game board having a batter's box, an infield and a channel runway defining the infield and extending from the right hand side of the batter's box to the left 25 hand side of the batter's box, said channel runway sloping toward its last named end and being provided at intervals along its length with vertical openings in the bottom thereof, stop members movable vertically in 30 said openings and normally in position to protrude from the openings into the channel runway, said game board having a second channel runway extending from the batter's box across the infield nearly to the intermediate 35 portion of the first named channel runway and having a third channel runway joined to the outer end of the second named channel runway and then extending across the infield to the left hand end portion of the first named channel runway, said game board having a vertical opening in the bottom of the second named channel runway at the outer end thereof, a control member 40 movable vertically in said last named opening and having a guiding and deflecting portion adapted to deflect a ball from the second named runway into the third named runway, and motion transmitting means connecting the control member with the stop which is 45 nearest to the left hand end of said first named runway, whereby the weight of a ball rolling down said second named channel runway against said control member will depress the latter and cause said stop to be 50 depressed from ball obstructing position.

21. In a game apparatus of the character described, a game board having an outerfield, an infield of diamond shape, and a channel runway dividing the infield from the outfield, said runway having spaced vertical openings in the bottom of the runway and stops movable vertically in said openings to and from positions to obstruct the 55 passage of a ball along said runway, a main

motion transmitting member, motion transmitting means connecting said main motion transmitting member with the stops and acting to hold said stops in ball obstructing position, and means adapted to be actuated by the weight of a ball projected onto the 60 outerfield to operate said main motion transmitting member to cause all of said stops to be depressed from ball obstructing position.

22. In a game apparatus of the character described, a game board having an outerfield, an infield of diamond shape, and a channel runway dividing the infield from the outfield, said runway having spaced vertical openings in the bottom of the runway 65 and stops movable vertically in said openings to and from positions to obstruct the passage of a ball along said runway, a main motion transmitting member, motion transmitting means connecting said main motion 70 transmitting member with the stops and acting to hold said stops in ball obstructing position, means adapted to be actuated by the weight of a ball projected onto the outerfield to operate the main motion transmitting 75 member to cause all of said stops to be depressed from ball obstructing position, and other means adapted to be actuated by the weight of a ball rolling in contact therewith to depress certain of said stops independently of the remaining stops.

23. In a game apparatus of the character described, a game board, a batting mechanism thereon comprising a back stop formed with an aperture therein, a propelling member hinged at its upper end in the upper end of said aperture and swingable forwardly and upwardly from the back stop, means for releasably holding said propelling member substantially in the plane of said 100 back stop, and spring means acting continuously to urge said propelling member to swing forwardly and upwardly from said 105 "set" position.

24. In a game apparatus of the character described, a batting mechanism comprising a vertically edgewise plate-like supporting member having an aperture therein, a propelling member supported at its upper end in said aperture to swing about a horizontal 110 axis forwardly and upwardly from a position in which the propelling member is inclined but slightly from the perpendicular, means for releasably holding said propelling member in rearwardly swung or "set" 115 position, spring means urging said propelling member to swing forwardly and upwardly from "set" position, said propelling member having a vertical slot intermediate its width, a trigger extending through said slot and adapted to be moved rearwardly in the slot by the impact of a ball thereagainst and to then operate said propelling member 120

holding means to effect release of the propelling member from said holding means, said propelling member having other vertical slots respectively located at opposite sides 5 of the first named vertical slot, means for causing an audible signal, and means protruding from the propelling member through said second named slots therein and adapted to be operated by the impact of a 10 ball thrown thereagainst to actuate said signal causing means.

25. In a game apparatus of the character described, a batting mechanism comprising a vertical support, a propelling member 15 supported in its upper end to swing about a horizontal axis, said propelling member having a rearwardly extending hook adjacent to its lower end, a swingable latch member spring pressed to position to engage said 20 hook to hold said propelling member substantially in the plane of said support, spring means urging said propelling member to swing from the plane of said support, and a trigger carried by said propelling 25 member operable to move said latch member out of engagement with said hook.

26. In a game apparatus of the character described, a game board, a batting mechanism thereon, a pitching mechanism having 30 a spring impelled throwing arm for throwing a ball toward the batting mechanism, and means for supporting said pitching mechanism for movement on the game board toward and away from said batting mechanism and for rocking movement about a 35 horizontal axis.

27. In a game apparatus of the character described, a game board having a vertical slot therein, a batting mechanism on the 40 game board toward which said slot extends, a handle extending loosely beneath said game board, a standard at the inner end of said handle extending through said slot, a frame secured rigidly to the upper end portion of said standard, a spring impelled 45 throwing arm carried by said frame and operable to throw a ball against said batting mechanism, and a slide member having a loose pivotal connection at its upper end with said frame for movably supporting the frame on said game board.

28. In a game apparatus of the character described, a game board having a vertical slot therein, a batting mechanism on the 50 game board toward which said slot extends, a handle extending loosely beneath said game board, a standard at the inner end of said handle extending through said slot, a frame secured rigidly to the upper end portion of said standard, a spring impelled 55 throwing arm carried by said frame and operable to throw a ball against said batting mechanism, a slide member having a loose

pivotal connection at its upper end with said frame for movably supporting the frame on 65 said game board, said slot being enlarged toward its lower end.

29. In a game apparatus of the character described, a game board having a vertical slot therein, a batting mechanism on the 70 game board toward which said slot extends, a handle extending loosely beneath said game board, a standard at the inner end of said handle extending through said slot, a frame secured rigidly to the upper end portion of said standard, a spring impelled 75 throwing arm carried by said frame and operable to throw a ball against said batting mechanism, a slide member having a loose pivotal connection at its upper end with 80 said frame for movably supporting the frame on said game board, a swingable spring actuated latch member engaging with said arm and normally holding said arm in "set" position, and motion transmitting 85 means carried by said handle for operating said latch member to release said arm.

30. In a game apparatus of the character described, a pitching mechanism comprising a frame having a pair of spaced side members, a rock shaft extending between said side members, a throwing arm rotatably supported at one end on the shaft, a torsion spring on said shaft for actuating said 90 throwing arm, and means for adjusting said spring to vary the torque which the spring exerts on said arm.

31. In a game apparatus of the character described, a pitching mechanism comprising a frame having a pair of spaced side members, a rock shaft depending between said side members, a throwing arm rotatably supported at one end on the shaft, a torsion spring on said shaft for actuating said 100 throwing arm, means for adjusting said spring to vary the torque which the spring exerts on said arm, a substantially cup-shaped holder carried by said arm at its free end, and a guide lip on said holder at 105 the rim edge thereof.

32. In a game apparatus of the character described, a pitching mechanism comprising a frame having a pair of spaced side members, a rock shaft depending between said side members, a throwing arm rotatably supported at one end on the shaft, a torsion spring on said shaft for actuating said throwing arm, means for adjusting said spring to vary the torque which the spring exerts on said arm, a substantially 110 cup-shaped holder carried by said arm at its free end, a guide lip on said holder at the rim edge thereof, and a bumper on said frame against which said arm is swung by said torsion spring.

JOHN WILLIS WEAVER.
